United States Patent Office

Des. 206,299
Patented Nov. 22, 1966

206,299

AIRCRAFT

Lawrence Bernard Rellis, 734 NW. 80th St., Apt. 16,
Miami, Fla.

Filed Mar. 7, 1966, Ser. No. 1,583

Term of patent 14 years

(Cl. D71—1)

Fig. 2

Fig. 3

Fig. 6

Fig. 7

FIG. 1 is a perspective view of the aircraft in the climbing position, showing my new design.

FIG. 2 is a side elevational view thereof;

FIG. 3 is a top plan view thereof;

FIG. 4 is an elevational view of the opposite side thereof;

FIG. 5 is a bottom plan view thereof;

FIG. 6 is a front elevational view in the landing position; and

FIG. 7 is a rear elevational view thereof.

I claim:

The ornamental design for an aircraft, as shown and described.
